SHIRT

Kathy Compton, Alexandria, Va. (14000 Castle Blvd., Apt. 103, Green Castle Country Club Apts., Silver Spring, Md. 20904)

Filed Aug. 4, 1971, Ser. No. 169,155

Term of patent 14 years

Int. Cl. D2—02

U.S. Cl. D2—46

FIG. 1.

FIG. 2.

FIG. 1 is a front elevational view of a shirt showing my new design, portions thereof not shown being conventional and unornamented; and

FIG. 2 is another embodiment of the design, portions not shown being conventional and unornamented.

I claim:

The ornamental design for a shirt, as shown.
